3 Sheets-Sheet 3

The image contains two technical line drawings of a device assembly, labeled Fig. 2 and Fig. 3.

Fig. 2: This cross-sectional view shows a cylindrical housing 27 containing a central tube 28. A flange 24 is attached to the top of the housing. A piston 20 is located within the tube 28, connected to a rod 17. A valve assembly 18, 21, 22 is positioned above the piston. A tube 26 is connected to the side of the housing 27. A rod 23 extends from the side of the housing, passing through a bearing 25 and a housing 16.

Fig. 3: This cross-sectional view shows a similar assembly. It features a flange 24, a piston 20, a valve assembly 18, 21, 22, and a tube 26. The piston 20 is connected to a rod 17, which is attached to a valve assembly 20, 21, 27. A tube 28 is connected to the side of the housing 27. A rod 23 extends from the side of the housing, passing through a bearing 25 and a housing 16. The housing 16 is shown in a different orientation in this view.

UNITED STATES PATENT OFFICE.

HERBERT O. EWING, OF MIDDLEPORT, OHIO.

INTERNAL-COMBUSTION ENGINE.

Application filed February 27, 1922. Serial No. 539,676.

To all whom it may concern:

Be it known that I, HERBERT O. EWING, a citizen of the United States, residing at Middleport, in the county of Meigs and State 5 of Ohio, have invented a new and useful Internal-Combustion Engine, of which the following is a specification.

This invention relates to internal combustion engines and more particularly to 10 that type of engine disclosed in my co-pending applications, filed November 15, 1919, Serial No. 338,312; and Sept. 2, 1921, Serial No. 498,012.

An object of this invention is to provide 15 a vacuum exhaust two-cycle engine having novel components constructed to insure perfect performance under all conditions of operation and especially when operating under a light load.

Another object of this invention is to provide 20 a vacuum exhaust two-cycle engine having its operating components so coordinated with relation to its intake and exhaust instrumentalities as to insure the maximum 25 efficiency of performance and economy during all phases of operation.

A further object of this invention is to provide 30 a vacuum exhaust internal combustion engine capable of producing a high vacuum within a vacuum cylinder to receive the exhaust gases from the power cylinders of the engine.

A further object of this invention is to provide 35 a two-cycle vacuum exhaust internal combustion engine of generally improved construction, whereby the device will be simple, durable and inexpensive in construction, as well as practical and serviceable in use.

With the foregoing and other objects in view which will appear as the description 40 proceeds, the invention resides in the combination and arrangement of parts and in the details of construction hereinafter described and claimed, it being understood that, within 45 the scope of what is claimed, changes in the precise embodiment of the invention shown can be made without departing from the spirit of the invention.

The invention has been illustrated in its 50 preferred embodiments in the accompanying drawing, wherein:

Figure 1 is a vertical sectional view, parts appearing in elevation.

Figure 2 is a transverse sectional view taken on the line 2—2 of Figure 1.

Figures 3 and 4 are diagrammatic views illustrating different phases of operation of the device.

Figures 5, 6 and 7 are diagrammatic views 60 depicting the relation existing between the crank shaft and the intake and exhaust instrumentalities during different stages of a cycle of operation.

Referring to the drawings, 10 designates 65 a crank case of an internal combustion engine, having a crank shaft 11 journaled thereon. A cylinder block is secured to the crank case 10 and comprises a primary or power cylinder 12 of relatively small bore 70 formed at that end of the cylinder block which is remote from the crank case, and a vacuum chamber or cylinder 13 of larger diameter is formed in the cylinder block 75 adjacent the crank case and communicates therewith. These cylinders communicate 80 with each other and are disposed in axial alignment and the head 14 of the cylinder 12 is rounded in order to aid in properly distributing the fuel charge, while a threaded aperture is formed in the head 14 at one side of its center for the reception of the usual spark plug P.

An intake port 15 extends inwardly and 85 upwardly through the wall of the cylinder 12 from an intake housing or manifold 16, and a combined transfer and exhaust port 17 leads from the primary cylinder 12 to the vacuum cylinder 13. The intermediate 90 portion of the exhaust port 17 communicates with the interior of an exhaust housing or manifold 18, and the outlet 19 of this manifold is offset laterally in order that valve supporting members may be carried by the housing. The valve supporting members 95 comprise radially aligned bearings 20 and 21 which slidably receive the stem 22 of a tappet or disk valve 23, and this valve 23 cooperates with a seat 24 formed at the point of communication between the exhaust port 17 and the exhaust manifold 18. A portion of the stem 22 is threaded to receive 100 an adjusting nut 25, and a helical spring 26 is positioned between the adjusting nut 25 and the inner face of the outer valve stem bearing 21. By this arrangement the valve stem bearing 20 is positioned exteriorly of the valve 23 so that when this valve is closed there can be no leakage past the valve stem 105 to the interior of the engine.

A composite piston structure is provided 110 and comprises a primary piston 27 slidably

within the primary cylinder 12 and secondary piston 28 slideable within the vacuum cylinder 13, and these pistons are provided with the usual packing rings. The head of the piston 27 extends longitudinally beyond the piston to provide a baffle head 29, and that portion of the baffle head 29 which is disposed adjacent the inlet port 15 is curved inwardly and upwardly in order to direct the incoming fuel charge towards the head 14 of the cylinder 12.

In order to insure a predetermined timed relation between the piston 27, intake port 15 and exhaust port 17, the crank shaft 11 is offset by journaling it to the crank case at points to one side of the axes of the cylinders 12 and 13, as indicated at 31, and this crank shaft is operably connected to the pistons through the medium of a connecting rod or pitman 32.

This crank shaft 11 is also provided with relatively long crank arms in order to impart a relatively long stroke to the primary and secondary pistons 12 and 13.

The cylinders 12 and 13 are provided with radial cooling fins, and since the cylinder 12 is subjected to higher temperature than the cylinder 13, it is provided with relatively long fins 33, and the cylinder 13, which during operation is exposed to less heat than cylinder 12, is provided with shorter fins 34. Since the vacuum cylinder 13 is necessarily larger than the primary cylinder, its relatively short fins are proportioned to terminate at the same distance from the axes of the cylinders as the terminals of the long fins 33, so that the general contour of the terminals of the fins 33 and 34 form a cylinder. Therefore in multi-cylinder engines the cylinders may be placed very close together and at the same time providing the primary cylinder, which is subjected to the most heat, with relatively long fins to aid in radiating the heat. The outer or head end of the cylinder 12 is provided with longitudinally extending fins 33' disposed at right angles to the fins 33, thereby greatly increasing the radiating surface at this point, which is obviously the hottest portion of the cylinder during operation.

It is highly advantageous that engines of this type be designed to operate in restricted spaces, such as the limited space beneath a washing machine, domestic mills and the like, and to this end I have so constructed the entire frame of the engine that the cylinders 12 and 13 will be slightly inclined, in which position the uppermost portions of the engine, such as the valve structure and the fly wheel 35, will be disposed approximately an equal distance from the ground or supporting base for the engine. In this position, the space provided by elevating the cylinder end of the frame is utilized by placing the fuel supply tank 36 under the cylinder,

and the fuel is fed from the tank 36 through a carburetor 37 and supply pipe to the intake housing or manifold 16, the carburetor 37 also being placed beneath the cylinders. Thus it is obvious that the entire device may be placed in a very restricted space; and as shown the upper portions of the highest components of the device will lie in an approximately horizontal plane so that the entire device may be readily placed under a washing machine or other structure, indicated by the dotted line in Figure 1.

In operation, a fresh charge of fuel is drawn in through the port 15 and is uniformly distributed within the cylinder 12 by means of the baffle head 29 and rounded cylinder head 14. The gases are then compressed and after ignition the force of the expanding gases move the pistons inwardly, and the secondary piston 28 creates a high vacuum in the cylinder 13. As the piston 27 nears the completion of its power stroke the exhaust port 17 is uncovered and the burnt gases are instantly drawn into the vacuum chamber 13. At this time the port 15 is uncovered and a new fuel charge is taken, and as the pistons move outwardly the primary piston 27 closes the port 15, and that terminal of the port 17 which opens into the cylinder 12, while the continued outward movement of the secondary piston 28 forces the valve 23 from its seat and drives the burnt gases from the vacuum chamber to the atmosphere.

When the primary piston 27 begins its power stroke doing work against an external resistance, this work is done at the expense of the energy in the gas resulting from its combustion, thus reducing both the temperature and pressure of the gases in the primary cylinder 12. The construction of the secondary or vacuum piston 28 and vacuum cylinder are such that during the vacuum producing stroke there is no communication whatsoever with any space exterior of the vacuum cylinder 13 and the port 17 until near the end of the vacuum producing stroke, when communication is established with the working or primary cylinder 12 through the port 17, which is made as short and direct as possible, the sectional area of this port being made as small as possible and yet allow the gases to pass from the primary cylinder into the vacuum cylinder in the time available, the exact dimensions of this port being determined by experiment to suit the conditions of fuel and engine speed. When the primary piston 27 uncovers the port 17 and establishes communication between the primary and vacuum cylinders, the gases in the primary cylinder 12 being at a much higher pressure than that prevailing in the vacuum cylinder, the gases from the primary cylinder flow into the vacuum cylinder with a very high velocity, 130

thus reducing the pressure in the primary cylinder very suddenly, and since both vacuum and primary pistons are still moving outwardly and doing work there is a 5 further reduction of temperature of the gases.

When the engine is operating under a very light load, the vacuum produced will be in excess of the requirements, but the 10 additional energy required to produce the excess vacuum is almost entirely recovered upon the return stroke of the secondary piston, and this return of energy on the compression stroke makes it possible to get exceedingly smooth operation at low speeds and light loads.

By starting the secondary or vacuum piston 28 on its vacuum producing stroke from a point as near the head of the vacuum cylinder as is practically possible and constructing this secondary piston and vacuum cylinder to so cooperate as to sever communication between the vacuum cylinder and any space exterior of the vacuum cylinder and exhaust port 17, and by restricting the size of this port to the minimum dimensions allowable and still secure exhaust in the allowable time; then the dead air or gas space at the beginning of the vacuum producing stroke is reduced to a minimum, and consequently, as the secondary piston moves towards the crank case, it produces a very high vacuum with a very small displacement because there is practically no residual gas 35 in the vacuum cylinder at the beginning of the vacuum producing stroke.

This arrangement is especially advantageous and essential to successful operation for the following reasons:

40 First:—The time available for the exhaust gases to flow from the working cylinder into the vacuum cylinder from the time the exhaust port opens until the inlet port is uncovered is a small fraction of a second 45 so that if the communicating passage between the two cylinders is to be made as small as possible so as to avoid excessive clearance volume, the velocity of the exhaust gases through this passage must be 50 very high and since the velocity of any fluid flowing from a region of high pressure to a region of low pressure is proportional to the square of the difference in pressures, it is evident that for a given terminal pressure 55 sure in the working cylinder, the lower the pressure produced in the vacuum cylinder, the more quickly the gases will flow from the working cylinder into it. If the gases do not flow from one cylinder to the other 60 in the time available the engine fails to operate.

Second:—The gases in the working cylinder at the time the exhaust port is uncovered are at a comparatively high temperature.

65 These gases are to mix with the residual

gases in the vacuum chamber. The temperature of the residual gases in the vacuum chamber at the end of the vacuum-producing stroke will depend upon the pressure at the end of this stroke, the lower the pressure 70 the lower the temperature (for a given initial temperature).

The lower the temperature of the residual gases in the vacuum chamber at the time these gases mix with those coming over from the working cylinder, the lower will be the temperature of the resulting mixture and consequently the lower the pressure of the mixture resulting in more work being returned to the working cylinder during its 80 compression stroke.

Third:—Unless the pressure in the working cylinder is reduced to below that of the atmosphere and this cylinder freed of burned gases quickly it will be impossible 85 to bring in a new fuel charge in the short time that the admission port is open because admission depends upon a sub-atmospheric pressure in the working cylinder while the admission port is open. A low 90 pressure in the vacuum cylinder is therefore necessary for the induction of a new fuel charge.

The three paragraphs just given are reasons why a high vacuum is essential to the 95 successful operation of this engine.

To so construct the vacuum cylinder and piston as to secure the greatest possible vacuum with the smallest possible displacement of the vacuum piston is essential for the 100 following reasons:

To produce a vacuum requires that work be done. In this construction, this work comes from the working cylinder and the net useful work is the difference between 105 the total work done in the primary or working cylinder and the work done in producing the vacuum; hence it is essential that the work done in producing the vacuum be kept as small as possible. The work required to produce a vacuum of a given pressure will depend upon the displacement of the vacuum piston; the smaller the displacement, the less the work. If the vacuum cylinder has a large amount of clearance volume, it will require a correspondingly large displacement to secure the vacuum necessary so that to secure a high vacuum with the minimum amount of work requires that 115 the vacuum cylinder be constructed with as little clearance as is practically possible. Engines constructed with a large amount of clearance would not function because the work required to produce the necessary vacuum would be more than the working 120 cylinder is capable of producing.

The term high vacuum as employed in the description of this invention is generally meant such a vacuum as could be produced by effecting practically zero clearance be- 125

tween the secondary piston and the vacuum cylinder head at the beginning of the vacuum producing stroke and severing communication between the vacuum cylinder and any space exterior of the vacuum cylinder and the restricted exhaust port during the vacuum producing stroke. More specifically it has been found by experiments that pressures within the vacuum cylinder varying between eleven and fourteen pounds per square inch below atmospheric pressure are essential to the successful operation of engines of this type.

When the engine is operating under a light load and at slow speed the pressure of the products of combustion will be reduced to atmospheric pressure within the primary cylinder 12 when the primary piston has traveled approximately the distance indicated by the arrow A in Figure 3, and continued movement of this piston, as indicated by the arrow B in Figure 4, produces a slight vacuum within the primary cylinder. After the port 17 has been opened, as indicated in Figure 4, the low pressure within both cylinders will tend to draw in air past the valve stem bearing 20, but this action is prevented by the described valve construction.

After the vacuum piston 28 has traveled far enough on the compression stroke to relieve the vacuum in the vacuum cylinder then a slight pressure is created in this cylinder which opens the valve 23 and forces the burnt gases from the cylinder to the atmosphere. Thus it is seen that part of the energy utilized in creating the vacuum in the vacuum chamber is restored on the return stroke, thereby producing a balancing action between the two pistons, and when operating under a light load the incoming new fuel charge does not raise the pressure within the primary cylinder to atmospheric pressure, then the slight vacuum resulting within this cylinder also aids in compressing the new charge and further balancing the cycle of operation. From the foregoing it is obvious that this arrangement permits a single port to transfer the gases from the primary cylinder to the vacuum cylinder, and to exhaust the gases to the atmosphere, and at the same time sealing the engine against the admission of the previously exhausted gases.

It has been found by experiment that in vacuum exhaust engines it is highly advantageous to provide relatively slow opening and quick closing exhaust instrumentalities and the most infinitesimal difference in the speed of opening and closing the exhaust port will add materially to the efficiency of the engine and to this end the crank shaft 30 has been offset relative to the axes of the cylinder. Referring to the diagrammatic Figures 5, 6 and 7, it will be

seen that as the piston 27 moves a distance sufficient to uncover the exhaust port 17 the crank has traveled through an arc C, as shown in Figure 5, and while closing this exhaust port the crank has traveled through an arc D. Since the arc D is shorter than the arc C it is obvious that the port closing action is quicker than the opening operation. Figure 6 depicts the arc of travel of the crank during the closing operation of the intake port and it is seen that the piston 27 completely covers the port when the crank is approaching the vertical portion of its arc of travel. Consequently the piston speed is being increased relative to the rotary speed of the crank. Arc E, in Figure 7, illustrates the travel of the crank while the piston 27 is moving from the closing position of the intake port 15 to the closing position of the exhaust port 17, and it is seen that after the closing of the intake port 15, the crank travels a very short distance before the exhaust port 17 is closed, thereby aiding in preventing any of the fresh charge being drawn into the vacuum cylinder with the exhausting burnt gases. Arc F shows the travel of the crank during the opening of the exhaust port 17 before the opening of the intake port 15, and since the arc F is greater than the arc E it is manifest that the opening of the exhaust port 17 before the uncovering of the intake port 15 is slower than the closing of the exhaust port 17 after the closing of the intake port 15. Therefore with this arrangement the high vacuum produced in the vacuum chamber 13 will remove the requisite portion of the burnt gases from the primary cylinder 12 before the incoming charge is admitted, and after the admission of the new charge and the closing of the intake port 15 the exhaust port is quickly closed to prevent the dissipation of the fuel charge. In order to obtain the highest possible vacuum within the vacuum cylinder 13, the pistons 27 and 28 are given relatively long strokes due to the relatively long crank arms of the crank 11, and to this end the pistons are given a stroke which is preferably equal to or greater than the diameter of the vacuum cylinder. This long stroke permits the ignited fuel charge, when operating under a normal or heavy load, to expand to substantially atmospheric pressure within the primary cylinder 12, thereby insuring fuel economy, which action is not possible in the existing two cycle engines having short strokes. The relatively long stroke of the secondary piston 28 creates a high vacuum within the vacuum cylinder 13, which action is aided by the restricted exhaust port 17 which only has sufficient transverse dimensions to permit the transfer of the burnt gases from the primary to the vacuum cylinder during the exhausting

period. By restricting the size of the exhaust port to the minimum dimensions consistent with free exhausting, and by starting the vacuum piston on its power stroke 5 from a point immediately adjacent the head of the vacuum cylinder then the dead air space at the beginning of the power stroke is reduced to a minimum and consequently as the vacuum piston moves towards the 10 crank case it produces a high vacuum because there is only a minimum amount of air in the vacuum cylinder and in communication with this cylinder at the beginning of the power stroke. At the end of the 15 power stroke the high vacuum instantly draws the requisite portion of the foul charge into the vacuum cylinder thereby reducing the pressure within the primary cylinder 12 to below atmospheric pressure 20 and consequently draws a fresh fuel charge into the primary cylinder of sufficient volume to insure complete charging. After the requisite portion of the foul charge has been transferred into the vacuum cylinder 25 18, the relatively long stroke of the secondary piston 28 within the relatively long vacuum cylinder 13 exposes this foul charge to the cooling action of the increased cooling surface of the vacuum cylinder 30 thereby materially reducing the pressure of these foul gases, which action lowers the pressure within the vacuum cylinder during a portion of the return or compression stroke to aid in compressing the fresh fuel 35 charge. During the relatively long compression stroke the fresh charge is highly compressed and consequently becomes highly sensitive, but owing to the peculiarly cooled cylinder head 14 preignition is prevented. This relatively long stroke aids in positively starting the engine because when the high vacuum thus created is communicated to the primary cylinder 12 it quickly produces sub-atmospheric pressure within 40 the power cylinder thereby drawing in sufficient fuel at the end of the first inward stroke of pistons to insure positive starting when fired at the end of the compression stroke. 45

Having thus described my invention what I claim is:

1. In an internal combustion engine, the combination of a primary cylinder, a vacuum cylinder positioned in axial alignment with the primary cylinder, an intake port communicating with the conventional carbureter and the primary cylinder, an exhaust port leading from the primary cylinder to the vacuum cylinder, and the terminal 55 of the exhaust port which communicates with the primary cylinder having greater dimensions in the direction of the axes of the cylinders than the terminal of the intake port which communicates with the primary cylinder, the ends of the said terminals of the intake and exhaust ports which are disposed away from the head of the primary cylinder being disposed equal distances from the head of the primary cylinder, a primary piston slidable within the primary cylinder, a secondary piston slidable within the vacuum cylinder and cooperating with the vacuum cylinder to create a high vacuum within this cylinder, a pitman operably connected to the said pistons, and a crank shaft journaled eccentrically of the axes of the said cylinders, and operably connected to the pitman to move the primary piston during a portion of its power stroke at a slower speed than is attained by the said piston during the same portion of its compression stroke, thereby causing the primary piston to open the intake and exhaust ports at a slower speed than said ports are closed to permit the high vacuum created within the vacuum cylinder to draw burnt gases from the primary cylinder into the vacuum cylinder, and to draw a new fuel charge into the primary cylinder and operating to segregate the new fuel charge from the burnt gases. 70 75 80 85 90 95
2. In an internal combustion engine the combination of a primary cylinder, a vacuum cylinder positioned in axial alignment with the primary cylinder, an intake port communicating with the conventional carbureter and the primary cylinder, an exhaust port leading from the primary cylinder to the vacuum cylinder, and the terminal of the exhaust port which communicates with the primary cylinder having greater dimensions in the direction of the axes of the cylinders than the terminal of the intake port which communicates with the primary cylinder, the ends of the said terminals of the intake and exhaust ports which are disposed away from the head of the primary cylinder being disposed equal distances from the head of the primary cylinder, a primary piston slidable within the primary cylinder, a secondary piston slidable within the vacuum cylinder to create a high vacuum in this cylinder, a pitman operably connected to the said pistons, and a crank shaft journaled eccentrically of the axes of the said cylinders, and operably connected to the pitman to cause this piston during its power stroke to uncover a portion of the exhaust port before uncovering the intake port at a slower speed than said portion of the exhaust port is covered during the return stroke, thereby permitting the high vacuum to draw the foul gases into the vacuum cylinder through this portion of the exhaust port during a longer period of time on the power stroke than during the return stroke. 100 105 110 115 120 125
3. In an internal combustion engine the combination of a primary cylinder, a vacuum cylinder disposed in axial alignment with the primary cylinder, an intake port 13

communicating with the primary cylinder and the conventional carburetor, an exhaust port leading from the primary cylinder to the vacuum cylinder and the terminal of the exhaust port which communicates with the primary cylinder having greater dimensions in the direction of the axes of the cylinders than the terminal of the intake port which communicates with the primary cylinder, the ends of the said terminals of the intake and exhaust which are disposed away from the head of the primary cylinder being disposed equal distances from the head of the primary cylinder, a primary piston slideable within the primary cylinder and constructed to cooperate with the said ports, a secondary piston slideable within the vacuum cylinder to create a high vacuum within this cylinder during the power stroke of the primary piston, a pitman operably connected to the said pistons, and a crank shaft journaled eccentrically of the axes of the said cylinders to uncover a portion of the exhaust port before uncovering the intake port at a slower speed than said portion of the exhaust port is covered during the return stroke to permit the said vacuum to reduce the pressure within the primary cylinder to below atmospheric pressure before the intake port is opened and thereby draw in a new fuel charge during the period the intake port is opened.

4. In an internal combustion engine the combination of a primary cylinder, a vacuum cylinder positioned in axial alinement with the primary cylinder, a primary piston slideable within the primary cylinder, an intake port communicating with the primary cylinder, an exhaust port leading from the primary cylinder to the vacuum cylinder, the terminal of the exhaust port which communicates with the primary cylinder having greater dimensions in the direction of the axes of the cylinders than the terminal of the intake port which communicates with the primary cylinder, said port terminals being disposed in such relation to each other and the primary piston as to cause the primary piston during the power stroke to open the exhaust port slightly in advance of opening the intake port, a secondary piston slideable within the vacuum cylinder and cooperating with the vacuum cylinder to produce a vacuum within this cylinder, a pitman operably connected to the said pistons, and a crank shaft journaled eccentrically of the axes of the said cylinders and operably connected to the pitman to move the primary piston during a portion of its power stroke at a slower speed than is attained by the said piston during the same portion of its compression stroke, thereby causing the primary piston to open the intake and exhaust ports at a slower speed than said ports are closed to permit the

vacuum created within the vacuum cylinder to draw burnt gases from the primary cylinder into the vacuum cylinder, and to draw a new fuel charge into the primary cylinder and operating to segregate the new fuel charge from the burnt gases.

5. In an internal combustion engine the combination of a primary cylinder, a vacuum cylinder positioned in axial alinement with the primary cylinder, a primary piston slideable within the primary cylinder, an intake port communicating with the primary cylinder, an exhaust port leading from the primary cylinder to the vacuum cylinder, the terminal of the exhaust port which communicates with the primary cylinder having greater dimensions in the direction of the axes of the cylinders than the terminal of the intake port which communicates with the primary cylinder, said port terminals being disposed in such relation to each other and the primary piston as to cause the primary piston during the power stroke to open the exhaust port slightly in advance of opening the intake port, a secondary piston slideable within the vacuum cylinder to produce a vacuum in this cylinder, a pitman operably connected to the said pistons, and a crank shaft journaled eccentrically of the axes of the said cylinders and operably connected to the pitman to cause the primary piston during its power stroke to uncover a portion of the exhaust port before uncovering the intake port at a slower speed than said portion of the exhaust port is covered during the return stroke, thereby permitting the vacuum to draw the foul gases into the vacuum cylinder through this portion of the exhaust port during a longer period of time on the power stroke than during the return stroke.

6. In an internal combustion engine the combination of a primary cylinder, a vacuum cylinder positioned in axial alinement with the primary cylinder, a primary piston slideable within the primary cylinder, an intake port communicating with the primary cylinder, an exhaust port leading from the primary cylinder to the vacuum cylinder, the terminal of the exhaust port which communicates with the primary cylinder having greater dimensions in the direction of the axes of the cylinders than the terminal of the intake port which communicates with the primary cylinder, said port terminals being disposed in such relation to each other and the primary piston as to cause the primary piston during the power stroke to open the exhaust port slightly in advance of opening the intake port, a secondary piston slideable within the vacuum cylinder to create a vacuum within this cylinder during the power stroke of the primary piston, a pitman operably connected to the said pistons, and a crank shaft journaled eccen-

trically of the axes of the said cylinders and operably connected to the pitman to cause the primary piston during its power stroke to uncover a portion of the exhaust port 5 before uncovering the intake port at a slower speed than said portion of the exhaust port is covered during the return stroke to permit the said vacuum to reduce the pressure within the primary cylinder to below atmospheric pressure before the intake port is opened and thereby draw in a new fuel charge during the period the intake port is opened.

7. In a two cycle internal combustion engine, the combination of a power cylinder having a piston connected to the crank shaft and a vacuum cylinder having a piston also connected to the crank shaft, said piston having substantially zero clearance with the 15 top of the vacuum cylinder, an intake port for said power cylinder thru which a fresh charge is aspirated, an exhaust port from the power cylinder to the vacuum cylinder thru which all of the spent gases are drawn 20 into the vacuum cylinder for subsequent exhaust to the atmosphere, said two ports being controlled by the power piston, and being so arranged that they are opened approximately at the end of the power stroke, the exhaust port opening before and closing 25 after the opening and closing of the intake port.

8. In a two cycle internal combustion engine, the combination of a power cylinder having a piston connected to the crank shaft and a vacuum cylinder having a piston also connected to the crank shaft, said piston having substantially zero clearance with the 30 top of the vacuum cylinder, an intake port for said power cylinder thru which a fresh charge is aspirated, an exhaust port from

the power cylinder to the vacuum cylinder thru which all of the spent gases are drawn into the vacuum cylinder for subsequent exhaust to the atmosphere, said two ports being controlled by the power piston, and being so arranged that they are opened approximately at the end of the power stroke, the exhaust port opening before and closing 45 after the opening and closing of the intake port, the parts being so proportioned that sub-atmospheric pressure obtains in both power and vacuum cylinders after a charge has been drawn in and the admission port 50 closed.

9. In a two cycle internal combustion engine, the combination of a power cylinder having a piston connected to the crank shaft and a vacuum cylinder having a piston also connected to the crank shaft, said piston 55 having substantially zero clearance with the top of the vacuum cylinder, an intake port for said power cylinder thru which a fresh charge is aspirated, an exhaust port from the power cylinder to the vacuum cylinder 60 thru which all of the spent gases are drawn into the vacuum cylinder for subsequent exhaust to the atmosphere, said two ports being controlled by the power piston, and being so arranged that they are opened approximately at the end of the power stroke, the exhaust port opening before and closing 65 after the opening and closing of the intake port, the parts being so proportioned that when the two cylinders are in communication the pressure in the vacuum cylinder never exceeds that in the power cylinder.

In testimony that I claim the foregoing as my own, I have hereto affixed my signature.

HERBERT O. EWING.
